E. J. BARRETT,
LOCK DEVICE FOR SHADE ROLLERS,
APPLICATION FILED FEB. 1, 1917.

1,236,393.

Patented Aug. 14, 1917.

Inventor
Edward J. Barrett,
By his attorney

Edward J. Barrett

UNITED STATES PATENT OFFICE.

EDWARD J. BARRETT, OF NEW YORK, N. Y.

LOCK DEVICE FOR SHADE-ROLLERS.

1,236,393.

Specification of Letters Patent. Patented Aug. 14, 1917.

Application filed February 1, 1917. Serial No. 145,832.

To all whom it may concern.

Be it known that I, EDWARD J. BARRETT, a citizen of the United States, and residing at New York, in the county of New York 5 and State of New York, have invented certain new and useful Improvements in Lock Devices for Shade-Rollers, of which the following is a specification, such as will enable those skilled in the art to which it appertains to make and use the same.

This invention relates to means for supporting shade rollers in position and for locking them against displacement, and the object thereof is to provide a combination 15 device of this class which is simple in construction and efficient in use, and which will prevent the accidental unwinding of the tension springs of rollers of the class specified, occasioned by the disengagement there- 20 of from the supports as usually constructed.

The invention is fully disclosed in the following specification, of which the accompanying drawing forms a part, in which the separate parts of my improvement are 25 designated by suitable reference characters in each of the views, and in which:—

Figure 1 is an inside view of the top portion of a window frame and indicating the use of my improvement;

30 Fig. 2 a face view of the combination support and lock device shown in Fig. 1 on an enlarged scale and indicating the angular shank at one end of the shade roller in section;

35 Fig. 3 a section on the line 3—3 of Fig. 2; Fig. 4 a section on the line 4—4 of Fig. 3;

Fig. 5 a face view of the base plate of my improved support and lock device with a lock spring secured thereto;

40 Fig. 6 an inside face view of the casing of the device; and,

Fig. 7 a face view of a lock plate which I employ.

In Fig. 1 of the drawing, I have indicated 45 at *a* the top portion of a window frame and at *b* the top sash of the window, and supported in the side portions *a*² of the frame is the usual shade roller *c*, the shank at one end thereof being mounted in the usual keeper 50 *c*², while the angular shank *c*³ thereof is mounted in or supported by my improved support and lock device *d*.

The support and lock device as shown 55 consists of a base plate *d*², a casing *d*³ and a lock plate *d*⁴, as shown in Figs. 5, 6 and 7 of the drawing.

Secured to the base plate *d*² by means of screws *d*⁵ is a flat sheet metal spring *e*, the top of which is provided with flaps *e*² bent at right angles thereto, and the central portion thereof with an aperture *e*³. The plate *d*² is also provided with a plurality of apertures *d*⁶ through which are passed screws, 60 nails, or the like for securing the device to the window frame, or one of the side members *a*² thereof.

The casing *d*³ is channel-shaped in form in cross section, or consists of a front plate *d*⁷ having side and bottom flanges *d*⁸ bent at right angles thereto, and which are adapted 70 to bear on the base plate *d*². The casing *d*³ is secured to the base plate by a screw *f* passed through an aperture *d*⁹ in said casing and into an aperture *d*¹⁰ in the base plate *d*², and the side flanges *d*⁸ of the casing 75 *d*³, when said casing is secured to the base plate *d*², pass outwardly of the flaps *e*² in the top portion of the spring *e*, and said flaps serve to hold the top portion of the casing *d*³ against movement as will be readily understood.

The bottom portion of the casing *d*³ is provided with an aperture *d*¹¹ in which is mounted a push button *g*, the inner end of which is provided with an enlarged head *g*² 85 adapted to bear on the bottom portion of the spring *e*, as clearly shown in Figs. 3 and 4. The top portion of the casing *d*³ is cut out centrally thereof to form an oblong aperture *d*¹² through which, in practice, the angular 90 shank *c*³ of the shade roller *c* is adapted to pass.

The lock plate *d*⁴ is provided in the top portion thereof with an angular aperture *h* through which, or in connection with which 95 the angular shank *c*³ of the shade roller *c* is adapted to operate, as indicated in Fig. 3 of the drawing, and the lower end portion of the lock plate *d*⁴ is provided with a backwardly directed stud *h*² which is 100 adapted to operate in connection with the aperture *e*³ in the lock plate *e*, as shown in said figure.

In the use of this device, the base plate *d*² is first secured to one side member of 105 the frame of a window, after which the casing *d*³ is secured to said base plate, the push button *g* being inserted in place in this last operation, after which the shade roller *c* is connected with the usual keeper *c*². The 110 lock plate *h* is then connected with the angular shank *c*³ of said roller, and said plate

is then forced downwardly into the lock device through the top thereof, the shank c^3 of the roller passing through the aperture d^2 in the casing d^3 in this operation, 5 and the downward movement of the lock plate d^4 over the spring e moves said spring inwardly until the stud h^2 on the plate d^4 comes in line with the aperture e^3 in said spring at which time said spring moves outwardly into the position shown in Fig. 3, 10 in which position the plate d^4 is held against movement, which in turn locks the shank c^3 of the roller c against displacement.

When it is desired to detach the shade 15 roller c from the window frame for cleaning the same, or substituting another therefor, all that is necessary to accomplish this result is to force the push button g inwardly to detach the spring e from the lock plate d^4 which permits the withdrawal of said 20 plate and the shank portion c^3 of the roller from the lock device as will be readily understood.

My invention is not limited to the details 25 of construction herein shown and described, and changes therein and modifications thereof may be made, within the scope of the appended claims, without departing from the spirit of my invention or sacrificing 30 its advantages.

Having fully described my invention, what I claim as new and desire to secure by Letters Patent, is:—

1. A support and lock device for the angular shank of shade rollers, comprising a spring, a casing inclosing said spring, a lock plate adapted to be connected with said angular shank and to be passed downwardly through said casing and engage said spring to lock the same and said shade roller against displacement, and means for operating said spring to release said plate.

2. A lock device for the shank of shade rollers comprising a casing, a spring mounted in said casing, and a lock member detachably connected with the shank of a

roller and adapted to operate in connection with said spring whereby said roller may be supported and held against displacement and a push button device mounted in said casing and adapted to release said spring from said lock member.

3. A support and lock device for the shanks of shade rollers, a casing, a spring mounted in said casing, said spring being provided with an aperture, a lock member provided with an aperture and a projecting member, said lock member being adapted to be connected with the shanks of shade rollers by passing said shanks through the aperture therein, the projection on said lock member being adapted to operate in connection with the aperture in said spring to lock the roller or a shank thereof in said casing, and means in said casing for releasing said spring from said lock member.

4. In a device of the class described, a casing composed of separate parts, the top portion of said casing being open and the front wall thereof being provided with an upwardly directed aperture, a spring mounted in said casing and provided centrally thereof with an aperture, a push button device mounted in the bottom portion of said casing and normally extended by said spring, and a lock member adapted to be passed downwardly through said casing and adapted to operate in connection with the aperture in said spring whereby said member is locked against displacement, said member being adapted to support the shank of a shade roller, said lock member being adapted to be released from said spring by means of said push button device.

In testimony that I claim the foregoing 85 as my invention I have signed my name in presence of the subscribing witnesses this 31st day of January 1917.

EDWARD J. BARRETT.
